UNITED STATES PATENT OFFICE.

ANDREW F. SHULER, OF ARCANUM, OHIO.

HUB.

SPECIFICATION forming part of Letters Patent No. 444,105, dated January 6, 1891.

Application filed December 9, 1889. Serial No. 333,050. (No model.)

To all whom it may concern:

Be it known that I, ANDREW F. SHULER, a citizen of the United States, residing at Arcanum, in the county of Darke and State of Ohio, have invented certain new and useful Improvements in Hubs, of which the following is a specification.

My invention relates to hubs for vehicle-wheels.

10 The object of my invention is to provide a hub having an outer shell or casing which extends entirely over the wooden portion of the hub, said shell or casing being made in two parts adapted to be forced onto the hub from 15 opposite ends thereof and joined together between staggered openings adapted to receive the spokes of the hub.

My invention consists in the various constructions hereinafter described, and set forth 20 in the claims.

In the accompanying drawings, Figure 1 is a side view of a hub embodying my invention, the outer shells thereof being shown in position for being forced onto the inner wooden 25 core. Fig. 2 is a sectional view of the same, showing the outer shells in position on the core. Fig. 3 is a similar view showing a slight modification in the construction of the outer shell. Fig. 4 is an enlarged view in detail and partly in section, showing the manner of joining the portions of the shell when constructed as shown in Fig. 2.

Like parts are indicated by similar letters of reference throughout the several views.

35 In the said drawings, A represents the inner core or hub proper.

B and B' represents, respectively, the different portions of the shell adapted to be forced onto the hub from the opposite ends 40 thereof. The part B, I preferably make long enough to extend beyond the hub at the rear and form a sand-band at D, the other or front portion B' being also long enough to extend in front of the hub and form a point-band D'. Each portion of the shell B and B' is provided with a series of openings C and C', adapted to come opposite and form a portion of similar openings E and E' in the core or hub proper, these openings, when in their 45 proper position, being staggered, as shown, to receive the spokes in a well-known manner.

On one portion of the shell, as at B, I form an outwardly-extending flange F, adapted, when that portion of the shell is in position on the hub, to stand between the respective 55 series of openings. This flange F is preferably made slightly thicker or heavier than the shell proper, and is provided with an annular recess or shoulder G, extending into the said shell about half the thickness thereof, and 60 adapted to receive the end of the other portion B' of the shell, which fits therein, as shown in Fig. 2 and in detail in Fig. 4.

The openings C and C' in the respective parts B and B' of the shell are formed at a 65 sufficient distance from the inner ends of said parts, so that when joined together, as above described, the inner edges of said openings stand substantially flush with the flange F. This flange F therefore forms a support for 70 the spokes in a well-known manner, while at the same time a sufficient amount of metal is left in the shell proper between the spokes to form a substantial support therefor and prevent any tendency of loosening on the part 75 of the shell.

In Fig. 3 I have shown the flange F formed partly on each of the shell portions B and B'. In this case the sand-band D and the point-band D' are shown separate, these constructions being adapted to be modified in either case, as preferred. When the point-band D' is made separate, as shown in Fig. 3, I preferably form that portion B' of the shell with which the point-band is to connect so that 85 when placed thereon the ends of the respective parts shall join together and form a substantial continuation of the shell.

It will be seen by the above construction that I form a hub in which a metallic shell 90 completely incases the inner or wooden portion of the hub. A solid or loose flange or ring is provided between the staggered openings, the parts being adapted to be forced onto the hub in opposite directions and join firmly 95 together and be held in proper position when the spokes are placed therein. By such construction the wheel is entirely protected and the wood equally compressed, forming a much superior construction than when the shell is 100 forced onto the hub from one direction only, leaving a portion of the wood exposed.

Having thus described my invention, I claim—

1. In a vehicle-hub, an outer shell or casing formed of two parts, each part being provided with a series of openings at a point slightly removed from the inner end of said part, said openings being adapted to stand in staggered series when the parts are in position on the hub, said parts being shaped to fit the respective ends of the hub, and adapted to be forced in opposite directions thereon and joined together at their inner ends, and a projecting flange of uniform thickness between the respective series of openings, substantially as specified.
2. The combination, with an inner hub or core, of an outer shell having a central projecting flange and staggered openings arranged in series on either side of said flange, said shell being divided into two parts, so that each series of openings shall stand slightly back of the dividing-line between the parts, whereby the shell may be placed onto said hub from opposite ends and joined together between the respective series of openings, substantially as specified.
3. The combination, with a hub or core, of an outer casing formed in two parts, one of said parts being provided with a projecting

flange having an annular recess therein 30 adapted to receive the inner end of the other part, the said parts being adapted to slip onto a hub from opposite directions, substantially as specified.

4. The combination, with an inner hub or core, of an outer shell or core made in two parts and adapted to extend entirely over said hub or core and form a point and sand band therefor, one of said parts being provided with a projecting flange and an annular recess and the other part being adapted to fit into said recess, substantially as specified.

5. The combination, with an inner hub or core, of an outer shell having staggered openings therein, a projecting flange between said staggered openings, and an annular recess in said flange adapted to receive the inner end of the other portion of the shell, which is forced onto said hub from the opposite direction, substantially as specified.

In testimony whereof I have hereunto set my hand this 4th day of December, A. D. 1889.

ANDREW F. SHULER.
